Primary Examiner — Wan Laymon(74) *Attorney, Agent, or Firm* — Alston & Bird LLP**CLAIM**

The ornamental design for a spool and bail valve, as shown and described.

DESCRIPTION

FIG. 1 is a perspective view of a spool and bail valve according to my new design;

FIG. 2 is another perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereto;

FIG. 9 is a perspective view of another spool and bail valve according to my new design;

FIG. 10 is another perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereto.

The broken lines are directed to environment and are for illustrative purposes only. The broken lines form no part of the claimed design.
